UNITED STATES PATENT OFFICE.

CHARLES E. CASHMAN, OF FITCHBURG, MASSACHUSETTS.

RUBBER HEEL-CUSHION.

1,165,847.

Specification of Letters Patent. Patented Dec. 28, 1915.

Application filed August 11, 1915. Serial No. 44,869.

To all whom it may concern:

Be it known that I, CHARLES E. CASHMAN, a citizen of the United States, residing at Fitchburg, in the county of Worcester and 5 Commonwealth of Massachusetts, have invented a new and useful Rubber Heel-Cushion, of which the following is a specification.

The object of my invention is to provide a rubber heel cushion adapted to be readily 10 inserted in the heel section of a shoe and to retain its position in the heel by reason of its novel construction.

In cushions of this class heretofore devised great inconvenience has resulted by 15 reason of the cushions becoming displaced from the heel section of the shoe, thus causing great discomfort to the wearer and retarding the sale of such heel cushions. This difficulty has been experienced even when 20 tacks have been used to fasten such cushions in place, as it has been found that the tacks are worked loose by the tendency of such cushions to work forward in the shoe.

It is the especial object of my invention 25 to provide a resilient heel cushion adapted to overcome this difficulty, and to provide a form of cushion adapted to retain itself in the heel section of the shoe, overcoming the discomfort of the cushion creeping down 30 under the arch of the foot, and eliminating the use of tacks to fasten the cushion in place in the shoe.

It is a further object of my invention to 35 provide an improved form of pneumatic heel cushion without increasing or complicating the manufacturing details or expense of material in producing the cushion for sale.

I attain the objects of my invention by 40 the mechanism illustrated in the accompanying drawings, in which—

Figure 1 is a plan view of the bottom of the cushion; Fig. 2 is a longitudinal section on line 2—2 of Fig. 1; and Fig. 3 is a trans- 45 verse section on line 3—3 of Fig. 2.

Like numerals refer to like parts throughout the several views.

Referring to the accompanying drawings, I provide a suitable upper heel strip or plat- 50 form member 1 of leather. To member 1 a suitable intermediate rubber strip 2 is cemented. To member 2 is cemented a bottom rubber cushion member 3, having a plurality of novel, forwardly-projecting ribs 4, hav- 55 ing the bottom edges of the ribs spaced apart one from the other and adapted to

engage with the heel section of the shoe to prevent the forward creeping which has been an objection to heel cushions heretofore devised. My cushion ribs 4 have their bottom 60 slanting surfaces 5 disposed in a gradual downwardly inclined plane, and their upper or forward slanting surfaces 6 disposed in an abrupt downwardly inclined plane, thus leaving a suitable space between consecutive 65 ribs, whereby to increase the cushioning effect of the device and also to cause an anti-creeping action of my heel cushion. The ribs are larger at the center and gradually decrease in size toward the forward and rear 70 ends of the heel cushion, as illustrated in Fig. 2. I provide suitable air chambers 7 between ribs 4 and intermediate strip 2, as illustrated in Figs. 2 and 3, to give a cushioning effect to the structure. 75

In operation, the bottom edges of the forwardly projecting ribs 4 make first contact with the bottom of the shoe and retain that point of contact as the pressure of the foot descends, causing a distinct backward 80 creeping of the cushion against the back of the heel chamber of the shoe. This causes the cushion to retain itself in the heel chamber of the shoe, without the use of tacks or cement, both of which means of fastening 85 heel cushions in place have been found defective and unreliable, or only of temporary usefulness. The anti-creeping action of ribs 4 of my heel cushion makes the use of tacks unnecessary. When the heel is raised, the 90 cushion tends to rebound rearward instead of creeping forward. The pneumatic chambers and spacing of the ribs gives the desired cushion effect to the structure. 95

What I claim is:

1. A heel cushion having forwardly slanting ribs adapted to engage the heel portion of the shoe, whereby to prevent the forward creeping of the heel cushion.
2. A heel cushion comprising an upper 100 leather platform, an intermediate rubber platform, and a bottom rubber cushion member having a series of forwardly slanting tapering ribs adapted to resiliently engage the heel portion of the sole to exert an anti-forward creeping action.
3. A heel cushion comprising a plurality of upper heel platforms and a bottom cushion member having forwardly projecting ribs spaced one from the other and having 110 air chambers within the rib members, whereby to increase the cushioning effect and to

prevent creeping forward of the device in the shoe.

4. A heel cushion comprising an upper leather heel platform, an intermediate rubber heel platform cemented thereto, and a bottom rubber cushion member cemented to the intermediate strip and having a series of forwardly-projecting ribs, with air chambers within the ribs, the forward surfaces of 10 the ribs being disposed at an abrupt downward inclination and the bottom surfaces of the ribs being disposed at a gradual downward inclination to space the edges of the ribs apart, whereby to increase the cushioning effect of the structure and to exert an

anti-creeping action of the ribs in contact with the shoe.

5. A heel cushion having a plurality of upper heel platforms and a bottom cushion member having a plurality of forwardly-projecting spaced ribs and having air chambers disposed within the ribs and adjacent to the superposed heel platform to which the cushion member is secured, said ribs being of graduated size decreasing in size toward the 20 forward and toward the rear portions of the heel platforms, substantially as shown and described, and for the purposes set forth.

CHARLES E. CASHMAN.
